UNITED STATES PATENT OFFICE

ALFRED TROSCH, OF ROCHESTER, NEW YORK, ASSIGNOR TO CONSOLIDATED MACHINE TOOL CORPORATION OF AMERICA, OF ROCHESTER, NEW YORK, A CORPORATION OF DELAWARE

APRON MECHANISM FOR LATHES

Application filed June 28, 1929. Serial No. 374,523.

This invention relates to improvements in machine lathes, and particularly to aprons for machine lathes on which the tools are mounted for longitudinal and transverse movement into operative engagement with a work piece.

The object of the invention is to simplify and at the same time render more efficient the clutch operating devices employed in the aprons of machine lathes.

Another object of the invention is to provide anti-friction thrust bearings for the gears for feeding the apron and tool carriage and for the clutch actuating devices.

To these and other ends, the invention consists in the construction and arrangements of parts that will appear from the following description when read in conjunction with the accompanying drawings, the novel features being pointed out in the claims following the specification.

In the drawings:

Figure 1 is a front elevation of a lathe apron constructed according to one embodiment of the invention.

Figure 2 is a section on line 2-2 of Figure 1, looking in the direction of the arrow at said line;

Figure 3 is a transverse section on line 3-3 of Figure 1, looking in the direction of the arrow at said line;

Figure 4 is a transverse section through one of the gear shafts showing how the shaft is mounted and also the clutch operating devices, and

Figure 5 is a fragmentary detail of the devices for locking a clutch operating device.

For convenience of illustration, the invention is shown as applied to a lathe of common and well known construction. Said lathe comprises a bed having guideways on which the apron may be moved along the work piece mounted in the dead and live centers. A revoluble lead screw is engaged by a split nut on the apron for moving the apron mechanically to feed the tool along the work piece.

A fixed rack is engaged by a pinion on the apron, which pinion is operated mechanically for imparting rapid movement to the apron or manually for feeding the tool to

the work piece or rapid manual movement. The work tools are mounted on a carrier movable transversely of the apron toward and from the work piece, the tool carrier being actuated either manually or mechanically. A clutch member rotates with the lead screw and is adapted to move in one direction or another from a neutral position to engage pinions operatively connected with the tool carrier or the fixed rack, intermediate clutch devices being provided for controlling the transmission of power.

The embodiment of the invention illustrated comprises an apron having a frame 1 in which the devices comprising the lathe 65 apron are mounted. To the rear of the apron is a revolving worm or lead screw 2, as usual in the art. Mounted on the screw to turn relatively thereto but mounted in bearings in the frame are bevel gears 3 and 4 spaced apart but facing each other. The gears 3 and 4 are provided with clutch members 5 and 6 respectively with which the teeth of a clutch member 7 are adapted to cooperate. The clutch member 7 is splined to the lead screw or slide thereon but rotates therewith. Each of the beveled gears 3 and 4 meshes with the bevel gear 8 secured to or formed integral with a shaft 9. When the clutch member 7 engages the clutch member 5, the gear 3 is connected to the lead screw to turn therewith and the gear 8 is turned in one direction. When, however, the clutch member 7 is moved out of engagement with the clutch member 5 and into engagement with the clutch member 6, the gear 8 is turned in the opposite direction. At an intermediate position, the clutch member 7 is out of engagement with both clutch members 5 and 6 and no motion is transmitted to the gear wheel 8.

Manually operated means are provided for sliding the clutch member 7 on the lead screw 2. To this end, the clutch member is provided with a circumferential groove 10, engaged by a stud 11 carried in an arm 12. The arm 12 is carried on the inner end of a shaft 13 revolvably mounted in the frame. At its other end, the shaft 13 has an operating arm 14 secured thereto. By moving the arm

14, the clutch member 7 may be moved into and out of engagement with the beveled gears 5 and 6. Means are also provided for locking the arm 14 in either a neutral position when the clutch member 7 turns independently of the gears 3 and 4, or in the positions in which the clutch member 7 turns either gear 3 or 4. To this end, the outer end of the arm 14 is provided with a spring pressed pin 15 which is adapted to engage one of the openings 16 provided therefor in the frame, one opening being provided for each of the three positions of the clutch member 7.

The forward end of the shaft 9 is provided with a gear 17 either secured thereto or formed integral therewith, which meshes with gears 18 and 19. The gear 18 is mounted on a sleeve 20 mounted to turn about an arbor 21 carried in the apron frame. The gear 18 is secured to the sleeve 20 by means of headed screws 22 seated in openings in a flange 23 on the sleeve and engaging threaded openings in the gear. The outer end of the sleeve 20 has a thrust bearing 24 threaded thereon and secured against displacement by means of a set screw. It will be noted that the sleeve 20 turns in a bearing member 22^a secured in the frame by means of headed screws. By this arrangement, the gear is fixed against axial movement relative to the frame but rotates freely relatively thereto. On the inner face of the gear 18 is provided one member 25 of a cone clutch, the other member 26 of which is mounted on the arbor 21 and has an inwardly extending hub 27 having a gear or pinion 28 secured thereto. It will be noted that when the clutch members are disengaged, the gear 18 idles on the arbor, but when the clutch members are engaged, the gear 28 turns as a unit with the gear 18.

Manually actuated means are provided for moving the clutch member 26 into and out of engagement with the clutch member 25. To this end, the arbor is mounted in the frame for axial movement, but splined against turning movement therein. The outer end of the arbor is supported in a bracket projecting forwardly from the frame and to which the outer end of the arbor is keyed. At its inner end, the arbor is keyed to the inner frame member 2^a. Adjacent its outer end the arbor is threaded at 30, and engaging this threaded portion is a nut 31 having a finger piece 32 by which it may be manually rotated. The nut 31 has a thrust bearing against the bracket 29 at its outer end and the roller bearings 33 are arranged between its inner end and the sleeve 20. By this arrangement, it is fixed against axial movement so that turning movements thereof move the arbor 21 axially through engagement with its threaded portion 30.

The roller bearings 33 are arranged between the nut 31 and the outer end of the sleeve or hub 20 on which the gear 18 is

mounted. Adjacent the outer face of the clutch member 26 the arbor 21 is enlarged to form a shoulder and seated between this shoulder and the clutch member is a collar 34. The hub of the gear 18 is provided with a recess 35 providing a clearance for axial movements of the collar. The hub of the clutch member 26 is mounted on a bushing 36, and the bushing and hub at their rear ends engage roller bearings 37 which are seated between the hub 27 and a bushing 38 retained on the inner end of the arbor by a nut 39 and keyed both to the frame and the arbor. When the arbor is moved axially from the position shown in Figure 4 by movement of the hand piece 32, the nut 39 on its inner end engages the bushing 38, and the movement of the arbor is transmitted to the clutch member 26 through the bearings 37. When the hand piece is turned in the reverse direction to disengage the clutch members, axial movement of the arbor is transmitted to the clutch member 26 through the collar 34 which engages its hub portion.

When the clutch members 25 and 26 are in engagement, the gear 28 rotates with the gear 18. The gear 28 meshes with a gear 40 mounted on a shaft 41 to turn therewith. The shaft 41 is rotatably mounted in the apron frame and at its rear end has a pinion 42 secured thereto to rotate therewith. The pinion 42 engages a rack 43 on the main frame 44 of the lathe, see Figure 3. Rotation of the pinion 42 in one direction or the other moves the apron on its guideways 44^a in one direction or the other.

Means are also provided for moving the apron manually. Said means comprises a gear or pinion 45 secured to or formed integral with a shaft 45^a revolvably mounted in the frame and meshing with the pinion 40. At its forward end, the shaft 45^a has a hand wheel 46 secured thereto by which the shaft may be manually rotated.

The pinion 19 is loosely mounted on an arbor 50 supported in the apron frame and is provided with one member of a cone clutch, the other member of which is mounted on the arbor for axial movement therewith and actuated by means of a hand piece 51 arranged on the forward end of the arbor. The movable clutch member has a pinion 52 connected therewith. The construction and operation is similar to that of the gear 18 and pinion 28 described above, and need not be described in detail.

The pinion 52 meshes with a gear 53 revolvably mounted in the apron frame, and the gear 53 engages a pinion 54 secured to or formed integral with a worm spindle 55 revolvably mounted in the frame, and operatively engages a tool carrier 56 of usual construction slidably mounted in guideways 57 for movement toward and from a work piece. The forward end of the spindle 55 may be

made angular in cross-section, as at 58, for engagement with a suitable tool by which the spindle may be manually operated.

It will be noted that when the gear 18 is disengaged from the pinion 28 and the gears 19 and 52 are connected by the clutch, turning movements of the bevel gear 8 in one direction or the other are transmitted to the worm 55 to move the tools in one direction or the other. If the gears 19 and 52 are disengaged from each other, and the gears 18 and 28 connected by the clutch devices, rotation of the bevel gear 8 in one direction or the other is transmitted to the pinion 42 to move the apron in one direction or the other.

Although only one embodiment of the invention is shown herein by way of illustration it will be understood that the invention includes all such changes or modifications as may come within the spirit or scope of the appended claims.

I claim:

1. A lathe comprising an apron, a train of gears on said apron, a sleeve on which one of said gears is mounted, a bearing in said apron in which said sleeve is revolubly mounted but fixed against axial movement, a clutch member on said gear, an arbor movable axially in said sleeve but fixed against rotation therein, a second gear revoluble on said arbor and movable axially therewith, a clutch member on said second gear adapted to cooperate with said first mentioned clutch member, and manually operated means on one end of said arbor for positively moving it axially to engage and disengage the clutch members.

2. A lathe comprising an apron, a train of gears on said apron, a sleeve on which one of said gears is mounted, a bearing in said apron in which said sleeve is revolubly mounted but fixed against axial movement, a clutch member on said gear, an arbor movable axially in said sleeve, a bracket on the apron in which said arbor is slidale, means in said bracket for fixing said arbor against rotation, a second gear revoluble on said arbor and movable axially therewith, a second clutch member on said second gear movable therewith to and from operative engagement with the first mentioned clutch member, and manually operated means revoluble on said arbor and engaging said bracket for moving the arbor axially to move the second clutch member to and from engagement with the first mentioned clutch member.

In witness whereof, I have hereunto signed my name.

ALFRED TROSCH.
